US00D920427S

(12) United States Design Patent (10) Patent No.: US D920,427 S
(45) Date of Patent: * May 25, 2021

(54) TYPE FONT(71) Applicant: Apple Inc., Cupertino, CA (US)(72) Inventors: Sebastian Johannes Bauer, San Francisco, CA (US); Aurelio Guzmán, San Jose, CA (US); Christopher Wilson, San Francisco, CA (US)(73) Assignee: Apple Inc., Cupertino, CA (US)() Term: 15 Years(21) Appl. No.: 29/725,272(22) Filed: Feb. 24, 2020*Related U.S. Application Data

(63) Continuation of application No. 29/684,049, filed on Mar. 18, 2019, now Pat. No. Des. 876,534, which is a continuation-in-part of application No. 29/642,805, filed on Apr. 2, 2018, now Pat. No. Des. 843,441, which is a continuation-in-part of application No. 29/590,601, filed on Jan. 11, 2017, now Pat. No. Des. 818,037.

Primary Examiner — Karen E Eldridge Powers(74) Attorney, Agent, or Firm — Sterne, Kessler, Goldstein & Fox P.L.L.C.(57) CLAIM

The ornamental design for a type font, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a face view of a type font showing the claimed design; and,

FIG. 2 is another embodiment thereof.

1 Claim, 2 Drawing Sheets
(1 of 2 Drawing Sheet(s) Filed in Color)
